UNITED STATES PATENT OFFICE.

JAMES S. HAGGERTY, OF MANNINGTON, WEST VIRGINIA.

CIGAR AND STOGY MAKING MACHINE.

1,239,004.

Specification of Letters Patent. Patented Sept. 4, 1917.

Application filed November 9, 1916. Serial No. 130,480.

To all whom it may concern:

Be it known that I, JAMES S. HAGGERTY, a citizen of the United States, residing at Mannington, in the county of Marion and State of West Virginia, have invented certain new and useful Improvements in Cigar and Stogy Making Machines, of which the following is a specification.

This invention relates to tobacco bunching and rolling machines for use in making cigars and stogies, and has especial reference to a machine which may be operated either by the hand or foot.

An object of prime importance is to provide a portable machine which may be used for bunching, rolling and wrapping the tobacco, so that the finished product is the result of a complete operation of the machine.

A coördinate object resides in the provision of a simplified structure which will automatically adjust itself to the "bunch" or "filler" of tobacco for making cigars or stogies of various sizes.

In the drawings:

Figure 1 is a top plan view of a machine constructed in accordance with my invention, a portion thereof being broken away.

Fig. 2 is a longitudinal sectional view of the same, and

Fig. 3 is a top plan fragmentary view of a modified form of the device.

In the drawings, a base member 1 is shown, to illustrate the application of my invention. A right-angled end portion 2 is secured to one of the terminals of the base 1, the latter being equipped with a sill 3, which snugly engages the said base and the end portion 2, as shown to advantage in Fig. 2.

Bearing blocks 4 are mounted upon the base 1, adjacent the opposite ends of the latter, and are provided with bearing sleeves in which the opposite ends of parallelly arranged shafts 5 are secured.

A carriage generally designated 6 is slidably mounted upon the shafts 5, and in this instance comprises a main frame 7 and a sub-frame 8. The main frame 7 consists of a pair of bearing sleeves 9 which are slidably mounted upon the shafts 5 and have web portions 10 extending upwardly therefrom into engagement with the bottom face of a smoothing plate 11. A roller 12 is journaled between the inner ends of the web portions 10, at a point off-set from the inner terminals of the bearing sleeves 9, as

shown to advantage in Fig. 2. The sub-frame 8 consists of a pair of bearing sleeves 13 which are also slidably mounted upon said shafts 5, in advance of the bearing sleeves 9. Web portions project upwardly from the outer periphery of the sleeves 13 and have journaled therebetween a roller 14 which extends in parallelism with the roller 12 and coacts therewith as will be hereinafter set forth. A shaft 15 is arranged between the web portions of said bearing sleeves 13 in superposed relation to a roller 16. Said roller 16 is journaled between the bearing sleeves 13.

A tensioning bracket 17 is reciprocably mounted upon the shafts 5 and is in yielding engagement with the end member 2 of the base. The yielding medium in this instance comprises a pair of coil springs 18, one end of each of which is in engagement with the bracket 17, while the opposite end of each is in engagement with a threaded bolt 19. The bolts 19 are adjustably mounted in the end member 2, so that the tension of the springs may be adjusted if so desired. It will be noted that the normal tendency of the springs 18 is to hold the bracket 17 in snug engagement with one of the bearing blocks 4.

In order to increase the efficiency of the work turned out by this machine, a master or retention belt 20 is provided which may be made of leather or any other suitable material. One end of the belt is fixedly engaged with the sill 3, while the opposite end is engaged with the upper face of the base 1. An intermediate portion of the belt is trained about the rollers 14 and 16, in order to hold the sub-frame 8 from movement, unless pressure is brought to bear on the latter. The carriage will in this way be stabilized, at the same time free movement of the carriage will be permitted when pressure is exerted thereon. In this way a smooth even movement of the carriage will be attained so as to adequately roll the tobacco bunch and insure the proper density of the cigar or stogy. As will be appreciated the master belt acts as a controller for the carriage without in any way retarding efficient operation of the latter. A tobacco "bunch" or "filler" apron 21 is provided, one end of which is fixedly engaged with the base 1, in superposed relation to the belt 20. The opposite end of the apron is engaged with the bracket 17, in the

form of the invention as shown in Figs. 1 and 2. The apron 21 is engaged over the rollers 12 and 14, as shown to advantage in Fig. 2, and is flexible between said rollers to provide a pocket. The main frame 7 and sub-frame 8 of said carriage are resiliently connected by springs 22, so that the space between the rollers 12 and 14 may be varied, to accord with the magnitude of the "bunch" or "filler" which is to be inserted in the pocket of the apron. The size of the pocket may be accordingly varied, due to the resilient mounting of the bracket 17.

In Fig. 3 a slightly modified form of the device has been shown. In this instance the springs 18 are shown directly connected to the apron 21, thereby eliminating the use of the bracket 17. The bracket 17 is desired when very accurate work is to be done, whereas by eliminating the bracket, a cheaper machine will be provided, and may be used equally as well, for work which need not be characterized by the greatest accuracy.

In operation, the "bunch" or "filler" is first assembled in the channel at the outer margin of the smoothing plate 11, after which the said "bunch" or "filler" is transferred to a point directly in front of the smoothing plate, which is directly above the rollers 12 and 14. By pressing downwardly on the "bunch" or "filler," the rollers 12 and 14 are separated, thereby permitting a pocket to be formed in the apron, the size of which is regulated by the size of the tobacco "bunch" or "filler." The carriage 6 is then moved toward the bracket 17, thereby rolling the contents of the pocket. If desired, the carriage may be moved on the shafts 5, until it contacts with the bracket 17, but as a general rule, the contents of the pocket will be sufficiently rolled, when approximately one-fourth the length of the shafts 5 has been traversed. Attention is also directed to the fact that the carriage may be operated by foot pressure if desired, in which instance a cable 23 is engaged with the stationary shaft 15 of the sub-frame 8, and is trained over a pulley wheel 24 in the base 1. The lower end of said cable is equipped with a stirrup 25 or the like, in which the foot may be conveniently placed. Pressure upon the stirrup 25, will obviously move the carriage toward the bracket 17.

When it is desired to expel the contents of

the pocket, the carriage is moved in the opposite direction.

From the above it will no doubt be obvious that a manually portable structure is provided, which can be manufactured at a very low cost, and which is characterized by its simplicity of operation and the fact that it is equally applicable for use in making cigars and stogies of various sizes.

I claim:—

1. A cigar and stogy making machine including a base equipped with a reciprocable carriage, a master belt, the terminals of which are engaged with said base, the body of the belt being trained through the carriage to insure a smooth even movement thereof, and an apron mounted on the base and flexible in the carriage to form a pocket.

2. A cigar and stogy making machine including a base equipped with horizontal shafts, a bracket movably mounted on the shafts and yieldably engaged with one end of the base, a carriage slidably mounted on the shafts and separable intermediate its ends, an apron, one end of which is engaged with said bracket and the opposite end engaged through the carriage and with said base, said apron being flexible between the separable portions of the carriage, to form a pocket.

3. A cigar and stogy making machine including a base equipped with parallelly arranged shafts, a bracket movably mounted on the shafts and yieldably engaged with one end of the base, a carriage slidably mounted on the shafts and separable intermediate its ends, a belt, one end of which is engaged with one end of the base, and the opposite end passed through said carriage and fixedly engaged with the base, adjacent the opposite end of the latter, to prevent undue movement of the carriage, and an apron, one end of which is engaged with said bracket and the opposite end engaged through the carriage and with said base, said apron being flexible between the separable portions of the carriage, to form a pocket, substantially as set forth.

In testimony whereof I affix my signature in presence of two witnesses.

JAMES S. HAGGERTY.
